CASING FOR AN ELECTRIC LAMP

Rene Marcel Angibaud, Vernon, France, assignor to Société les Piles Wonder

Filed July 16, 1970, Ser. No. 23,981

Claims priority, application France Feb. 18, 1970

Term of patent 14 years

Int. Cl. D26—02

U.S. Cl. D48—24

FIG. 1 is a front perspective view of a casing for an electric lamp embodying my new design;

FIG. 2 is a rear elevational view thereof;

FIG. 3 is an elevational view of one side thereof;

FIG. 4 is an elevational view of the other side thereof;

FIG. 5 is a top view thereof, the bottom view being similar thereto; and

FIG. 6 is a rear elevational view showing a modification of my design, all other views remaining the same.

I claim:

The ornamental design for a casing for an electric lamp, as shown and described.
